STRAIN DEVICE

Herbert E. Miller, Allentown, Pa., assignor to
 Utilities Service Company, Inc., Allentown, Pa.,
 a corporation of Pennsylvania

Application January 4, 1933, Serial No. 650,153

6 Claims. (Cl. 248—31)

This invention relates to strain devices, and more particularly to a strain device adapted for general application such, for example, as a strain insulator clevis, pipe hanger, etc.

5 In my copending application Serial No. 636,565, filed October 6, 1932, I have disclosed various forms of strain insulator clevises each embodying a flexible insulator embracing member and a two piece yoke member having arms secured to the 10 ends of the flexible member. In each instance, the two elements of the yoke member have interfitting or inter-engaging portions which serve to anchor the elements against movement with respect to each other. Such clevises are particularly intended for use where the clevises are not rigidly connected to supports such as poles or the like.

An important object of the present invention is to provide a strain device capable of general application and more particularly to stationary installations as in the case of a strain insulator clevis, pipe hanger or the like, wherein installation may be quickly and readily accomplished.

25 A further object is to provide an insulator clevis of the same general character as the clevises disclosed in my copending application referred to except that the present construction is particularly adapted for use where the clevis is to be maintained in fixed relationship with respect to 30 a support such as a pole.

35 A further object is to provide a device of the character referred to wherein a rigid two piece yoke is employed and is adapted to be secured to a fixed support, and wherein the means for securing the device to the support is operative for securing the elements of the yoke in fixed relationship with respect to each other.

40 A further object is to provide a strain device embodying a two piece yoke one of which is provided with an opening or recess adapted to receive a portion of the other yoke element to prevent movement of the yoke elements laterally with respect to the line of pull on the device, and to provide novel means for utilizing the element which secures the device to the desired support for preventing movement of the yoke elements longitudinally with respect to the line of pull.

45 Other objects and advantages of the invention will become apparent during the course of the following description.

In the drawings I have shown two embodiments of the invention. In this showing:

50 Figure 1 is a side elevation of the device shown in position with respect to a supporting pole,

Figure 2 is an enlarged face view of the device, Figure 3 is a section on line 3—3 of Figure 1; Figure 4 is an edge elevation of the device, Figure 5 is a sectional view showing the device in elevation employed as a pipe hanger,

5

Figure 6 is a detailed perspective view of a shim employed in connection with the device and, Figure 7 is a detailed section on line 7—7 of Figure 5.

In Figures 1 to 4 inclusive the device has been 10 illustrated as a strain insulator clevis. Referring to Figure 1, the numeral 10 designates a supporting pole of any of the usual types to which is connected a cross arm 11 for any desired purpose. This cross arm is secured to the pole by 15 suitable bolts one of which is illustrated and designated by the numeral 12. The bolt carries a head 13 at one end and a nut 14 at the other, as shown in Figure 1.

The device forming the subject matter of the 20 present invention comprises a flexible body 15 preferably formed of stranded cable wherein the strands are formed of steel wire copper coated to protect them from rust or corrosion. The flexible member normally occupies the position shown in 25 Figure 2 including straight parallel arms 16 connected by a curved portion 17. The flexible member is adapted to embrace a strain insulator 17' to which is connected a wire of the usual type 18.

A yoke indicated as a whole by the numeral 30 19 forms a part of the insulator clevis and is formed of separate pieces 20 and 21. The yoke members include arms 23 and 24 respectively which diverge toward the ends of the cable arms 16 and have their extremities preferably butt 35 welded to the extremities of the arms 16. The yoke member 20 includes a head 25 having a central opening 26 through which the bolt 12 extends. The head 25 is further provided with a recess radially offset from and communicating 40 with the opening 26 for a purpose to be described.

The yoke member 21 is provided with a lug portion 28 corresponding in shape to and adapted to be received in the opening 27. The lug portion 28 is offset from the adjacent end of 45 the arm 24 to form a shoulder 29 which seats against the inner face of the head 25, and to form a shoulder 30 engageable with the nut 14. The arms 23 and 24 are preferably slightly cut away at their inner portions adjacent the head 25 50 as at 31 to form shoulders adapted to lie against the nut 14 to prevent rotation thereof.

In Figures 5, 6 and 7 the device has been illustrated for use as a pipe hanger. The principal 55 elements of the device may be identical with

the corresponding elements previously referred to and accordingly such elements have been designated by the same reference numerals. Referring to Figure 5, it will be noted that the device is arranged in vertical position when used as a pipe hanger and the bolt 12 is of a suitable nature to extend through a horizontal support 32. The head 25 seats against the lower face of the support 32, as shown, and the nut 14 retains the yoke elements in proper position.

One or more pipes may be supported by the device, and in Figure 5, one pipe 33 has been shown arranged within the flexible member 15. A suitable preferably metallic shim 34 forms a seat for the pipe. This shim is substantially U-shaped and includes vertical arms 35 connected by a substantially semi-circular portion 36 fitting within the loop portion of the flexible member 51. Adjacent their upper ends, the arms 35 are provided with inwardly stamped lips 37 which straddle the opposite arms 16 of the flexible member to prevent displacement of the shim laterally with respect to the supports. The lips 37 may be bent inwardly into engagement with the arms 16 of the flexible member as shown in Figure 7.

The operation of the form of the device shown in Figures 1 to 4 inclusive is as follows:

With the parts of the yoke separated, the flexibility of the cable section 15 permits the yoke elements to be separated whereby the insulator 17 readily may be placed in position within the cable. The yoke elements are then moved toward each other with the lug element 28 arranged inwardly of the head 25, until the lug element is in alignment with the opening 27, whereupon it is inserted in such opening. With the parts in this position, it will be apparent that the walls of the opening 27, engaging the surfaces of the lug element 28, will prevent outward movement thereof.

The device is then ready to be placed in position with respect to the pole 10, and as previously stated, the bolt 12 may be employed for this purpose. However, it will be apparent that the device may be directly connected to the pole 10 instead of to the cross arm 11, and it also will be apparent that a separate bolt may be used for securing the clevis to the pole. In either case, however, the device is placed in position with respect to the pole after the elements have been assembled in the manner described, whereupon the bolt 12 is inserted and tightened in position. This bolt obviously serves the purpose of holding the clevis rigidly in operative position by engagement between the nut 14 and the adjacent face of the head 25. At the same time, the nut 14 engages the shoulder 30 to prevent movement of the lug element 28 out of its opening 27. When the bolt 12 is in position it engages the adjacent face of the lug element 28 thus preventing radially inward movement of the lug element, and accordingly the bolt 12 and the walls of the opening 27 cooperate to prevent movement of the lug element 28 in any direction in a plane at right angles to the line of pull on the insulator. Movement of the lug element and its associated yoke member longitudinally of the line of pull obviously is prevented by the nut 14. Thus it will be apparent that this nut serves the double purpose of securing the clevis in position with respect to the fixed support and at the same time fixes the yoke members 20 and 21 against movement with respect to each other. The device is very simple in construction and is readily assembled

and applied without the use of special tools of any kind.

The operation of the form of the invention shown in Figures 5, 6 and 7 will be obvious from the foregoing description. One or more pipes may be supported within the flexible member 15 and the bolt 12 serves to support the device to carry the weight of the pipe, while the head of the bolt 14 seats against both the head 25 and projection 28 to anchor these elements in proper operative positions. The shim 34 is not essential to the operation of the device but its use is preferred for the reason that it provides a broad bearing seat for the pipe.

It is to be understood that the forms of the invention herewith shown and described are to be taken as preferred examples of the same and that various changes in the shape, size and arrangement of parts may be resorted to without departing from the spirit of the invention or the scope of the subjoined claims.

I claim:

1. A device of the character described comprising a flexible article embracing member, and a yoke formed of a pair of complementary members each secured to one end of said flexible member, one of said complementary members being provided with an opening extending longitudinally with respect to the flexible member and surrounded by the material of such complementary member, the other complementary member having a projecting portion corresponding in shape and size to and movable longitudinally into said opening, the members of said pair having portions facing in the direction of said flexible member and lying substantially in the same plane to be engaged by a common securing element.

2. A device of the character described comprising a flexible article embracing member, a yoke formed of a pair of complementary members each secured to one end of said flexible member, one of said complementary members being provided with an opening therethrough substantially longitudinally with respect to the flexible member and surrounded by the material of such complementary member, and being further provided with a second opening adjacent said first named opening to receive a portion of the other complementary member inserted thereinto longitudinally with respect to said flexible member, and a fastening member adapted to be inserted through said first named opening and provided with a head arranged inwardly of said yoke, said complementary members being provided with inner face portions lying substantially in a common plane at right angles to the plane of the flexible member and engageable with the head of said fastening member.

3. A device of the character described comprising a flexible article embracing member, a yoke formed of a pair of complementary members each secured to one end of said flexible member, one of said complementary members being provided with a relatively large flat integral head arranged substantially at right angles to the plane of the flexible member and having its outer face engageable against a support, said head being provided with an opening arranged substantially longitudinally of said member for the reception of a fastening element for securing said head to the support, said head being further provided with an opening adjacent and parallel to said first named opening, both of said openings being surrounded by the material of said head, the other complementary member having a projection correspond-

- ing in shape and size to said second named opening and adapted to be inserted thereinto substantially longitudinally with respect to said flexible member, said last named complementary member having a shoulder lying in the plane of the inner face of said head, and a fastening element passing through said first named opening and having a head engageable with said shoulder and the inner face of said head, said first named opening embracing said fastening element to prevent lateral movement of said head with respect to said fastening element.
4. A device constructed in accordance with claim 3 wherein each complementary member is provided with an arm connected to one end of said flexible member, said arms having shoulders engageable with the head of said fastening element to prevent rotation thereof.
5. A device of the character described comprising a flexible article embracing member, a yoke formed of a pair of complementary members each secured to one end of said flexible member, one of said complementary members being provided with a relatively large flat integral head arranged substantially at right angles to the plane of the flexible member and having its outer face engageable against a support, said head being provided with an opening arranged substantially longitudinally of said member for the reception of a fastening element for securing said head to the support, said head being further provided with an opening adjacent and parallel to said first named opening and communicating therewith, said head having a continuous unbroken peripheral portion surrounding said openings, the other complementary member having a projection corresponding in shape and size to said second named opening and adapted to be inserted thereinto substantially longitudinally with respect to said embracing member, said last named complementary member having a shoulder lying in the plane of the inner face of said head.

responding in shape and size to said second named opening and adapted to be inserted thereinto substantially longitudinally with respect to said article embracing member, said last named complementary member having a shoulder lying in the plane of the inner face of said head, and a fastening element passing through said last named opening and having a head engageable with said shoulder and the inner face of said head.

6. A device of the character described comprising a flexible article embracing member, and a yoke formed of a pair of complementary members each secured to one end of said flexible member, one of said complementary members being provided with a relatively large flat integral head arranged substantially at right angles to the plane of the flexible member and having its outer face engageable against a support, said head being provided with an opening arranged substantially longitudinally of said member for the reception of a fastening element for securing said head to the support, said head being further provided with an opening adjacent and parallel to said first named opening and communicating therewith, said head having a continuous unbroken peripheral portion surrounding said openings, the other complementary member having a projection corresponding in shape and size to said second named opening and adapted to be inserted thereinto substantially longitudinally with respect to said embracing member, said last named complementary member having a shoulder lying in the plane of the inner face of said head.

HERBERT E. MILLER. 35
